TROUSERS HANGER

Joseph D. Cudd, Boise, Idaho

Application March 8, 1957, Serial No. 644,921

1 Claim. (Cl. 223—88)

The present invention relates to trousers hangers, and more particularly to such devices which are adapted for attachment to coat hangers.

The primary object of the invention is to provide a trousers hanger of the cuff engaging type which is adapted to be supported on and clamped to an ordinary wire coat hanger.

Another object of the invention is to provide a device of the class described above which can be molded from plastic material and is inexpensive to manufacture, simple to use, and quite durable in heavy service.

Other objects and advantages will become apparent in the following specification when considered in the light of the attached drawings, in which:

Figure 1 is a fragmentary side elevation with parts broken away for convenience of illustration.

Figure 2 is a top plan view of the invention shown removed from the coat hanger with trousers shown attached thereto in dotted lines.

Figure 3 is an end elevation of the invention.

Figure 4 is a fragmentary vertical cross-section taken along the line 4—4 of Figure 1, looking in the direction of the arrows.

Figure 5 is a fragmentary horizontal cross-section taken along the line 5—5 of Figure 1, looking in the direction of the arrows.

Figure 6 is an enlarged fragmentary horizontal cross-section taken along the line 6—6 of Figure 1, looking in the direction of the arrows.

Referring now to the drawings in detail wherein like reference characters indicate like parts throughout the several figures, the reference numeral 10 indicates generally a trousers hanger attachment for wire coat hangers constructed in accordance with the invention.

The trousers hanger 10 comprises a pair of elongated relative thin flat frame members 11 and 12 which are arranged in closely adjacent spaced parallel relation and are of identical configuration. Each of the frame members 11 and 12 are provided with oppositely extending reduced end portions 13. The reduced end portions 13 are each bifurcated by means of a slot 14 extending longitudinally thereof so that the reduced end portion 13 is resilient.

A support, generally indicated at 15, is affixed to each end of the frame members 11 and 12 and depends therefrom. The support 15 comprises a pair of spaced parallel upright bars 16 and 17 having their upper ends substantially thickened at 18 and 19, respectively, and joined by a bight 20 extending therebetween at an angle to the horizontal. The thickened portions 18 and 19 are each provided with parallel longitudinally extending slots 21 and 22 of a size to receive and grip the reduced end portion 13 of the frames 11 and 12, respectively.

The bars 16 and 17 are provided with opposed detents 23 and 24 adjacent the bight 20 but spaced therefrom. The bars 16 and 17 are further provided with pairs of interengaging detents 25 and 26 adjacent the lower ends, for reasons to be assigned.

The bars 16 and 17 are reverted at 27 and 28, respectively, and are provided with an outwardly offset upper

2

extension 29 and 30, respectively, as best seen in Figure 3. Horizontally extending pants engaging plates 31 and 32 project integrally from the outwardly offset portions 29 and 30, as best seen in Figure 5.

5 The supports 15 being mounted on opposite ends of the frames 11 and 12 are arranged with the plates 31 and 32 extending toward the center of the frames 11 and 12. It should be noted that the upper edges of the plates 31 and 32 are provided with a relatively sharp edge 33 and 10 34, respectively, to assist in forming a sharp lower crease in the trousers.

The hanger 10 is adapted for attachment to a wire coat hanger generally indicated at 35 which includes a horizontal lower bar 36 and a pair of upwardly sloping 15 top bars 37 and 38 extending from opposite ends of the lower bar 36. The wire coat hanger 35 is of conventional design and forms no part of the present invention.

In attaching the trousers hanger 10 to the wire coat hanger 35, the sloping bars 37 and 38 are engaged under 20 the opposite bights 20 of the supports 15, as seen in Figure 1, with the detents 23 and 24 engaged thereunder to assist in securing the hanger 10 to the coat hanger 35.

The lower bar 36 of the coat hanger 35 is engaged 25 between the detents 26 on the bar 17 and held therein by one of the detents 25 on the bar 16, as shown in Figure 4. Obviously, in the case of a slightly larger coat hanger 35, the lower bar 36 will be engaged between the detents 25 and held there by the detent 26.

From the above description it can be seen that the 30 bar 16 of each of the supports 15 extends down one side of the coat hanger 35, and the bar 17 extends down the other side of the coat hanger 35 assuring that the hanger 10 will not be displaced from the coat hanger 35 in use.

After attaching the trousers hanger 10 to the coat 35 hanger 35, the plates 31 and 32 are engaged under the cuff portions 39 and 40 on a pair of trouser legs 41 and 42. The cuff 39 is engaged over the plate 31 on one of the supports 15 and on the plate 32 of the other support 15 with the trouser leg in extended position. The coat 40 hanger 35 is then hung on a closet pole in the usual manner so that the trousers, generally indicated at 43, are suspended therefrom in creased position.

Having thus described the preferred embodiment of the invention, it should be understood that numerous 45 structural modifications and adaptations may be resorted to without departing from the scope of the appended claim.

What is claimed is:

50 A trouser hanger attachment for one piece wire coat hangers of the type including a horizontal lower portion and inwardly and upwardly sloping opposed upper portions integrally formed on opposite ends of the lower portion comprising a pair of flat coextensive laterally spaced parallel frame members, a reduced end portion formed integrally on each of the opposite ends of each of said frame members, a pair of longitudinally spaced vertically extending supports, said supports each having a pair of spaced parallel slots engaging over the adjacent reduced end portions of said frames, and a pair of laterally spaced 55 trouser cuff engaging plates integrally secured to the lower end of each of said supports, said plates each being reverted outwardly from its respective support and extending upwardly from the lower end thereof.
